C. F. Randolph

INVENTOR

L. M. Poole,

BY *Victor J. Evans*

ATTORNEY

UNITED STATES PATENT OFFICE.

LUCIA MELISSA POOLE, OF SAN JOSE, CALIFORNIA.

MOP-HEAD.

1,268,769.

Specification of Letters Patent.

Patented June 4, 1918.

Application filed March 7, 1917. Serial No. 153,094.

To all whom it may concern:

Be it known that I, LUCIA MELISSA POOLE, a citizen of the United States, residing at San Jose, in the county of Santa Clara and

5 State of California, have invented new and useful Improvements in Mop-Heads, of which the following is a specification.

The present invention relates to improvements in the construction of mop heads,

10 adapted for holding mop rags, dusting cloths and other articles, and the primary object of the invention is to simplify and improve the existing art by producing an article of this character which shall be of an extremely

15 simple construction, wherein the cloth or rag may be easily and quickly removed when desired, and which may be cheaply manufactured and marketed.

With the above and other objects in view 20 the improvement resides in the construction, combination and arrangement of parts set forth in the following specification and falling within the scope of the appended claims.

In the drawing:

25 Fig. 1 is a perspective view of a mop head constructed in accordance with the present invention,

Fig. 2 is a view illustrating the arrangement of parts when the mop cloth is to be 30 arranged upon or removed from the mop head,

Fig. 3 is a sectional view approximately on the line 3—3 of Fig. 1, and

Fig. 4 is a sectional view approximately 35 on the line 4—4 of Fig. 2.

The head essentially includes a metal substantially U-shaped yoke or frame 1, the connecting member of the same being centrally provided with a socket 2 which receives the handle 3. One of the side members or arms of the frame has its end formed with an eye 4, while the opposite arm is bent upon itself to provide what I will term a hook 6. Pivotal secured to the eye 4 is 40 a bar 7, the free end of the said bar being provided with a loop 8 to engage with the hook 7. Slidably mounted upon the arms of the frame is a second bar 9, which has both of its ends provided with eyes 12, one

45 to engage with the hook and the other to contact with the eye of the arms of the frame, and it will be noted that this last mentioned member 9 when moved in the direction of the handle will be brought out of engagement with the first mentioned bar whereby to 50 permit of the said first mentioned bar being

disengaged from the hook of the frame and swung away from the frame. Pivotal secured to the socket 2 is a substantially rounded spring member or bail 11 that has 60 its outer end formed with an inwardly extending rounded depression 12 that is adapted to engage with the inner bar of the device and to force the latter into frictional contact with the first mentioned bar. 65

By swinging the spring bar away from the inner bar it will be noted that the said inner bar may be moved longitudinally of the side members of the frame and out of frictional contact with the second bar, and if desired 70 the said second bar may be released from its engagement with the hook of the frame and swung outwardly therefrom, so that mop rags or the like of different dimensions may be easily and quickly arranged upon the device or removed therefrom as desired. 75

Form the above description, taken in connection with the accompanying drawing, the simplicity of the device as well as the advantages thereof will, it is through, be perfectly apparent to those skilled in the art to which such invention appertains without further detailed description. 80

Having thus described the invention, what I claim is:

1. In a device for the purpose set forth, a socket designed to receive a handle, a substantially U shaped frame centrally connected to the socket, a rod pivotally secured to the end of one of the arms of the frame, means 90 for removably securing the second end of the rod to the second arm of the frame, a second rod slidably mounted on the arms of the frame, a spring ring member hingedly connected with the socket and having an inwardly extending rounded depressed portion designed, when the ring is brought to one position, to engage with the second mentioned rod to move the same in the direction of the first mentioned rod and to hold 95 the said second mentioned rod against the first mentioned rod. 100

2. In a device for the purpose set forth, a socket designed to receive a handle, a frame comprising a member formed to provide 105 spaced parallel arms which are inclined angularly and inwardly at their inner ends, and the central portion of the said frame passing centrally through the socket, one of the arms of the frame having its end provided 110 with an eye, the second arm of the said frame having its end inturned to provide a

hook, a bar having both of its ends formed with eyes, one of said eyes engaging with the eye of the frame and the other designed to be engaged by the hook of the frame, a second bar having its ends formed with eyes which are arranged on the parallel arms of the frame, whereby the said second mentioned rod is slidably connected to the frame, a spring ring member passing through the 10 socket at the end thereof, and arranged at a right angle with respect to the longitudinal

plane of the frame, and said ring having an inwardly depressed portion at the outer side thereof, designed to engage with the slidable rod to move the same outwardly of the frame 15 and to retain the said slidable rod in frictional engagement with the pivoted rod, when the ring is swung in a line with the socket and the handle connected with the socket. 20

In testimony whereof I affix my signature.
LUCIA MELISSA POOLE.

Copies of this patent may be obtained for five cents each, by addressing the "Commissioner of Patents,
